UNITED STATES PATENT OFFICE.

SYLVANUS S. VAN KEUREN, OF ABERDEEN, SOUTH DAKOTA.

INCUBATOR.

1,160,793.

Specification of Letters Patent. Patented Nov. 16, 1915.

Application filed June 12, 1915. Serial No. 33,705.

To all whom it may concern:

Be it known that I, SYLVANUS S. VAN KEUREN, a citizen of the United States, resident of Aberdeen, in the county of Brown and State of South Dakota, have made a certain new and useful Invention in Incubators; and I declare the following to be a full, clear, and exact description of the same, such as will enable others skilled in the art 10 to which it appertains to make and use the invention, reference being had to the accompanying drawings, and to letters or figures of reference marked thereon, which form a part of this specification.

15 Figure 1 is a perspective view of the invention. Fig. 2 is a section on the line 2—2, Fig. 3 is a section on the line 3—3, Fig. 4. Fig. 4 is a section on the line 4—4, Fig. 3. Fig. 5 is a section on the line 5—5, Fig. 4. Fig. 6 is a detail perspective view 20 of the removable heater.

The invention has relation to incubators, and it consists in the novel construction and combinations of parts, as hereinafter set 25 forth.

In the accompanying drawings, illustrating the invention, the numeral 2 designates the casing, having usually a framing provided upon each side and top and bottom 30 with wooden insertion strips or panels 3 upon the outside, and fiber-board strips 4 upon the inside and spaced apart from the wooden strips or panels, to provide dead air spaces 5 for insulating purposes, said fiber- 35 board strips meeting at the corners of the casing. At the center of the casing is a narrow vertical heating chamber, provided at each side with a metal plate 7, the two plates forming the side walls of said chamber 40 and terminating near the bottom of the casing, from which they are separated by intervals 8, said heating chamber having a top 9 carrying a laterally extending deflector strip 10, located near the top and extending 45 from end to end of the casing.

At each side of the heating chamber is an egg chamber 11, having an outer side wall 12 separated from the fiber-board strip by a space 13, constituting a second dead air or 50 insulating space, and an inner side wall 14, located close to the radiator plate at this side. In each egg chamber are a plurality of egg trays 15, usually two, one over the other and having suitable support, usually 55 sliding in guideways 15', doors 16 in the front of the casing leading to the egg cham-

bers, said doors being hinged at the bottom at 16' and having suitable top catches 17, each door being provided with double panes of glass or mica, separated by an air space 60 for insulation.

Fitting removably within the heating chamber is the radiator pipe 18 of a heater, including a vertical metal casing 18' located exteriorly of the incubator and divided by a horizontal partition 19 into upper and lower chambers 20, 20'. The heating tube has horizontal upper and lower branches 21, 21', connected by an inner bend 22, the outer end of the upper branch having communication 70 with the upper chamber and the outer end of the lower branch terminating in a vertical tube 23, located in the lower chamber and designed for the introduction of a suitable source of heat supply, as a lamp or the chimney thereof. The upper branch of the heating tube terminates about centrally of the lower portion of the upper chamber, the heated air spreading in said chamber and its circulation being retarded. The retarding 75 or upper chamber has a top hood or stack 20², provided with lateral air exit openings 20³.

The lower chamber is provided with an inner lining 24, spaced apart from the walls 85 proper of said chamber and having a packing of asbestos or the like in the interval. This inner lining is also in the form of a vertical tube, of larger diameter than the tube 23, from which it is separated by a 90 space 25. The tube 24 has a horizontal branch 26, of larger diameter than and surrounding the outer end of the heating tube branch 21', said branch 26 having communication with the heating chamber for the introduction of fresh air, which passes in through the open bottom of the tube 24. The outer end of the heating tube, being nearest the lamp, is guarded by side plates 27, 27. Usually the vertical metal casing of 95 the heater has a backing 28 of wood and fiber-board, to which the casing is secured, the guard plates 27 having a cover strip 29 of wood or the like and a bottom strip 30 of the same material, both strips being carried by said backing, said bottom strip being 100 a little longer than the heater tube and at its inner end having an upwardly extending metal support 31 therefor.

The backing of the heater forms a closure 110 or door for the open end of the heating chamber, the bottom strip resting upon the

bottom of the heating chamber, and the exterior metal casing being supported through engagement of the backing 28 with the upper and lower walls of the end of the heating chamber.

5 Below the heating chamber a moistening tray 32 is provided, said tray sliding in a supporting and inclosing box 33, the top of said box being provided with a series of 10 perforations or slots 35 communicating with a slot 37 of the bottom strip of the heater, said slot communicating with the heating chamber. The moistening tray is suitably provided with water, usually being filled 15 with sand saturated with water. This tray and its inclosing box are closely jointed, and are designed to be practically airtight.

Projecting above the top of the incubator, centrally thereof and running from front 20 to back, is a ventilator 38, communicating with the interior of the casing by a slot 39 in the top of the casing, said slot being guarded by one or more thicknesses of thin 25 felt 40, in order to impede the circulation of the air. The ventilator is provided with a suitable top 41, a vertical passage 42, guarded at the top by a screen 43 against the admission of insects and dust, and lateral openings 44, leading from said passage.

30 The egg trays are provided each with a bottom 45 of fiber-board and a false bottom 45' of wire screen cloth, located above and separated from the fiber-board bottom by a space 45², in which sand is located. The 35 eggs are turned twice daily, in practice, the trays being at the same time turned end for end and the bottom tray being placed at the top and vice versa, the trays being suitably numbered or tagged for identification.

40 The intermixed heat and fumes from the lamp are confined to the heater proper, and are not allowed entrance to the heating chamber or to the egg chambers.

45 The heated air in the heating chamber, the temperature of which is made higher by the side radiator plates, will pass out at the bottom at each side, under said radiator plates and under the lower egg trays, passing 50 thence endwise of the egg chambers under the egg trays and up through passages 46 between the ends of the egg trays and the end walls of the egg chambers, the outer sides of the egg trays making a close joint 55 with the sides of the egg chambers, to prevent rising of the heated air except at the ends of the trays. The heated air as it rises above the upper egg trays will be deflected outwardly by the deflector strip, and will 60 pass around the outer edges of said strip into the narrow passage between the deflector strip and the top of the egg chambers, through the felt strips and up through the ventilator. The circulation of the heated air is always horizontal and upward, and

never downward, and this circulation is made less rapid by the retarding felt strips of the ventilator, whereby the amount of heat required is reduced. The fresh air passing into the heating chamber is mixed 70 with moisture from the moistening tray before it is admitted to the egg chambers.

What I claim is:—

1. In an incubator, lateral egg chambers, a central heating chamber, egg trays in said 75 chambers having imperforate bottoms extending entirely across said chambers, the lower of said trays and the bottoms of the egg chambers being spaced apart to provide horizontal air passages and the said trays being spaced apart from the ends of said chambers to provide vertical air passages, said heating chamber having side walls provided with bottom openings in communication with said horizontal air passages. 80

2. In an incubator, lateral egg chambers, a central heating chamber, egg trays in said 85 chambers having imperforate bottoms extending entirely across said chambers, the lower of said trays and the bottoms of the 90 egg chambers being spaced apart to provide horizontal air passages and the said trays being spaced apart from the ends of said chambers to provide vertical air passages, said heating chamber having side walls composed of metal plates provided with bottom 95 openings in communication with said horizontal air passages, and a deflecting strip carried by the top of the heating chamber and extending laterally partly over the egg 100 trays, and spaced apart from the top of the egg chambers to provide upper horizontal air passages, a ventilator communicating with said upper horizontal air passages, and a moistening tray located below and communicating with the bottom of said heating chamber. 105

3. In an incubator, lateral egg chambers, a central heating chamber, egg trays in said 110 chambers having imperforate bottoms extending entirely across said chambers, the lower of said trays and the bottoms of the egg chambers being spaced apart to provide horizontal air passages, and the trays being spaced apart from the ends of said chambers to provide vertical air passages, said heating chamber having side walls provided with bottom openings in communication with said horizontal air passages, and a removable heater for the heating chamber including a reversely bent tube having its ends opening exteriorly of said chamber. 115

4. In an incubator, lateral egg chambers, a central heating chamber, egg trays in said 120 chambers having imperforate bottoms extending entirely across said chambers, the lower of said trays and the bottoms of the egg chambers being spaced apart to provide horizontal air passages, and the trays being spaced apart from the ends of said 125 130

chambers to provide vertical air passages, and a deflecting strip carried by the top of the heating chamber and extending laterally partly over the egg trays, said heating chamber having side walls provided with bottom openings in communication with said horizontal air passages, and a removable heater including a reversely bent tube having its ends opening exteriorly of said chamber, a lamp tube connected to the lower end of the heating tube, and a fresh air inlet tube surrounding the lamp tube having communication with said chamber.

5. In an incubator, lateral egg chambers, a central heating chamber, egg trays in said chambers having imperforate bottoms extending entirely across said chambers, the lower of said trays and the bottoms of the chambers being spaced apart to provide horizontal air passages, and the trays being spaced apart from the ends of said chambers to provide vertical air passages, a deflecting strip carried by the top of the heating chamber and extending laterally partly over the egg trays, said heating chamber having side walls provided with bottom openings in communication with said horizontal air passages, and a removable heater including a reversely bent tube having its 25 ends opening exteriorly of the said chamber, a lamp tube connected to the lower end of the heating tube, a fresh air inlet tube surrounding the lamp tube and communicating with said chamber, a retarding box surrounding the upper end of said heating tube, a moistening tray underlying the heating chamber and having communication therewith, and a ventilator overlying the heating chamber.

40 6. In an incubator, lateral egg chambers, a central heating chamber, egg trays in said chambers having imperforate bottoms extending entirely across said chambers, the lower of said trays and the bottoms of the 45 egg chambers being spaced apart to provide horizontal air passages, and the trays being spaced apart from the ends of said chambers to provide vertical air passages, said chamber having side walls provided with bottom openings in communication with said horizontal air passages, a deflecting strip extending laterally partly over the egg trays and spaced apart from the top of the egg chambers to provide upper horizontal 50 air passages, said egg trays having upper screen bottoms spaced apart from the lower imperforate bottoms.

55 air passages, a moistening tray underlying

the heating chamber and having communication with the bottom thereof, and a ventilator overlying the heating chamber and having communication with said upper horizontal air passages.

60

7. In an incubator, lateral egg chambers, a central heating chamber, egg trays in said chambers having imperforate bottoms extending entirely across said chambers, the lower of said trays and the bottoms of the 65 egg chambers being spaced apart to provide horizontal air passages, and the trays being spaced apart from the ends of said chambers to provide vertical air passages, said chamber having side walls provided with bottom openings in communication with said horizontal air passages, a deflecting strip extending laterally partly over the egg trays and spaced apart from the top of the egg chambers to provide upper 70 horizontal air passages, and a removable heater comprising a door for the open end of the heating chamber, a bottom strip resting upon the floor of said chamber, a reversely bent tube having its ends opening 75 exteriorly of the said chamber and supported by said door and bottom strip, a lamp tube connected to the lower end of said tube and a retarding box surrounding the upper end of said tube.

85

8. In an incubator, lateral egg chambers, a central heating chamber, egg trays in said chambers having imperforate bottoms extending entirely across said chambers, the lower of said trays and the bottoms of the 90 egg chambers being spaced apart to provide horizontal air passages and the trays being spaced apart from the ends of said chambers to provide vertical air passages, said chamber having side walls provided with bottom openings in communication with said horizontal air passages, a deflecting strip extending laterally partly over the egg trays and spaced apart from the top of the egg chambers to provide upper horizontal 95 air passages, said egg trays having upper screen bottoms spaced apart from the lower imperforate bottoms.

100

In testimony whereof I affix my signature, in presence of two witnesses.
